UNITED STATES PATENT OFFICE

132,764

DESIGN FOR A PULL TAB FOR SLIDE FASTENERS

Samuel F. La Verde, Niagara Falls, N. Y., assignor
to Mary La Verde, Niagara Falls, N. Y.

Application March 27, 1942, Serial No. 106,350

Term of patent 7 years

To all whom it may concern:

Be it known that I, Samuel F. La Verde, a citizen of the United States, residing at Niagara Falls, in the county of Niagara and State of New York, have invented a new, original, and ornamental Design for a Pull Tab for Slide Fasteners, of which the following is a specification, reference being had to the accompanying drawing, forming part thereof.

Figure 1 is a front elevational view of a pull tab for slide fasteners showing my new design, the opposite side being plain.

Figure 2 is a side elevational view thereof.

I claim:

The ornamental design for a pull tab for slide fasteners, as shown and described.

SAMUEL F. LA VERDE.
